US0D1002840S

(12) **United States Design Patent** (10) **Patent No.:** **US D1,002,840 S**
(45) **Date of Patent:** **** Oct. 24, 2023**

(54) **SYRINGE PLUNGER**

(71) Applicant: **Bayer HealthCare LLC**, Whippany, NJ (US)

(72) Inventors: **Kevin Cowan**, Allison Park, PA (US); **John Haury**, Sewickley, PA (US)

(73) Assignee: **Bayer Healthcare LLC**, Whippany, NJ (US)

(**) Term: **15 Years**

(21) Appl. No.: **29/751,090**

(22) Filed: **Sep. 18, 2020**

Related U.S. Application Data

(60) Continuation of application No. 16/946,008, filed on Jun. 2, 2020, now abandoned, which is a continuation of application No. 15/851,860, filed on Dec. 22, 2017, now Pat. No. 10,668,221, which is a continuation of application No. 14/576,354, filed on Dec. 19, 2014, now Pat. No. 9,855,390, which is a division of application No. 11/686,000, filed on Mar. 14, 2007, now Pat. No. 8,926,569.

(57) **CLAIM**

The ornamental design for a syringe plunger, as shown and described.

DESCRIPTION

FIG. 1 is a bottom view of a syringe plunger showing our new design in accordance with an embodiment of the invention;

FIG. 2 is a front elevation view thereof, the rear elevation view being a mirror image thereof;

FIG. 3 is a left side elevation view thereof, the right side elevation view being a mirror image thereof;

FIG. 4 is a lower perspective view;

FIG. 5 is a first cross-sectional view thereof; and,

FIG. 6 is a second cross-sectional view thereof. The portions of the syringe plunger shown in broken lines form no part of the claimed design.

1 Claim, 6 Drawing Sheets
